[57] CLAIM

The ornamental design for a hangtag for a sports cap, as shown.

DESCRIPTION

FIG. 1 is a front elevation view of a hangtag for a sports cap embodying our new design;

FIG. 2 is a side elevation view of FIG. 1, the other side not shown being a mirror image of the side shown in this view; FIG. 3 is a rear view of of FIG. 1;

FIG. 4 is a reduced front elevational view thereof; and, FIG. 5 is a perspective view of FIG. 4.

The broken lines showing the outlines of a sports cap in FIGS. 4 and 5 is for illustrative purposes only and forms no part of the claimed design.
